US0D1070094S

(12) **United States Design Patent** (10) **Patent No.:** **US D1,070,094 S**
(45) **Date of Patent:** **** Apr. 8, 2025**

(54) **SILICONE GEL FILM DRESSING**

(71) Applicant: **Huizhou Foryou Medical Devices Co., Ltd.**, Huizhou (CN)

(72) Inventors: **Xiaodong Liu**, Huizhou (CN); **Wei Lu**, Huizhou (CN); **Mingming Ma**, Huizhou (CN)

(73) Assignee: **HUIZHOU FORYOU MEDICAL DEVICES CO., LTD.**, Huizhou (CN)

(**) Term: **15 Years**

(21) Appl. No.: **29/799,284**

(22) Filed: **Jul. 13, 2021**

(30) **Foreign Application Priority Data**

Jun. 29, 2021 (CN) 202130406919.1

CLAIM

The ornamental design for a silicone gel film dressing as shown and described.

DESCRIPTION

FIG. 1 is a front elevational view of a silicone gel film dressing according to a first embodiment of our design;

FIG. 2 is a rear elevational view thereof; and,

FIG. 3 is an exploded perspective view thereof.

The oblique shade lines in the drawings show transparency.

1 Claim, 3 Drawing Sheets
